C. W. JONES

COMBINED RAZOR AND BLADE HOLDER

Filed Feb. 21, 1924

Inventor
Charles W. Jones
by
H. C. Johnson
Att'y.

14. The present invention relates to a shaving device, and more particularly to a combined safety razor and blade holder.
15. In a satisfactory shaving it is essential that the cutting edge of whatever device is used be as sharp as possible. In order to provide an edge that will readily remove an growth of beard from the face, it is desirable to sharpen the blade at the beginning of each shaving operation. Stropping alone will maintain the edge in good condition for a certain length of time, but it is necessary to cut three to four times to provide a new edge by means of honing. These are various devices which it is possible to use in conjunction with a blade holder, means of stropping and honing, but where a shaving is performed with the safety razor, the blade holder is provided simply a hinged piece of metal having a slot on one of its edges; it is usually necessary to use a separate honing device than for cutting which is blade and another for stropping it.
16. The object of the present invention is to hold the blade during a sharpening operation by means of the safety razor itself.
17. Another object of the invention is to combine with a safety razor, means whereby will indicate by touch the position of a blade.
18. Another object is to improve and simplify the holding means for a blade.
19. In order to attain these objects, I provide in accordance with one feature of my invention a hinged blade holding a threaded opening into which may be screwed an adjustable gripping jaws shaving integral therewith, and guiding means for a blade and blade jaws.
20. A blade is provided to receive a blade which will be positioned and guided therewith respect to the gripping jaws, shaving integral therewith, and guiding means for a blade and blade jaws.
21. Figure 1, is a view in side elevation of a safety razor incorporating the present invention.
22. Figure 2, is a view in front elevation thereof.
23. Figure 3, is a view in front elevation of the device with the blade set for an angle in stroke.
24. Figure 4, is a view in side elevation of the device in use during a double edge shaving.
25. Figures 5 and 6, show the positive, and side elevations of an arm with which is incorporated a guiding extension; and
26. Figure 7, is a view in side elevation of the gripping jaws.
- Referring to the drawings in detail:
- The assembled device as used for shaving is illustrated in Figures 1 to 3.
- A blade 1 is provided with an threaded aperture interior thereof, into which may be screwed an threaded shaft 2 having a curved arm 3 and a hinged base 4. The periphery of the blade may be furnished as shown to provide a convenient means for gripping the handle. A handle 5 may be provided with lateral extensions 6 and this handle is provided with a central opening large enough so that it may be easily slipped over the threaded portion of the handle 2 while assembling these parts. Lateral extensions 7 on each of the curved arms 3 and 4 are smoothly machined to provide a guide and prevent lifting off the device during a stropping operation. Integral with arms 3 and 4, respectively, are plates 8 and 9 on any suitable metal each plate being provided in its forward edge with a notch 10, of a size to conveniently receive a point 11, integral with a plate base portion 12 integrally connected to a safety razor head 13 of a well known type. When this is mounted with guiding means for a blade and blade jaws, the safety razor blade may be provided in the place of plate 12 to any desired angle with respect to the handle 1. This may be accomplished by unscrewing the handle from the threaded shaft 2 and base of the gripping jaws, turning the handle with the correct angle in stroke and may also be inserted point 11 as a pivot and again firmly securing

the head between the gripping jaws by screwing the handle onto threaded shank 2. When the handle is unscrewed to release the gripping jaws, the ferrule 5 is also released 5 and is free to be rotated about the shank 2. When the handle is thus loosened, the ferrule may be positioned with the guiding extensions in a desired position with respect to the plane of plate 12, the position to conform to the requirements of the individual 10 using the device. When the handle is again screwed onto the threaded shank 2 to tighten the gripping jaws, the ferrule is thereby firmly secured in position. The regulation of the position of the lateral extensions on the ferrule to that of plate 12 being known, the user may, since, in the normal use of the device, his hand is in contact with the lateral extensions thereof during 15 a shaving operation, be able to determine at all times the position of the razor blade with respect to his hand. This feature is especially desirable when shaving in a poor light or without a mirror.

25 When it is desired to use the device for sharpening a blade, the gripping jaws are loosened by unscrewing the handle and the safety razor head is removed. A blade 13 may then be inserted between the gripping 30 jaws and the handle again screwed tight to cause the jaws to firmly grip the blade, as shown in Figure 4. The degree of curvature of the arms 3 and 4 is predetermined and is such that, when the device is being 35 used for honing or stropping, as shown in Figure 4, and the blade is inserted between the jaws a predetermined amount, lateral extensions 6 or 7 will rest flat upon the surface of the hone 14 or strop 15, and the edge 40 of blade 13 will be positioned against the surface of the hone or strop at a predetermined angle, to produce a cutting edge of maximum efficiency.

45 In honing a blade, the device is conveniently held in the hand and lightly pressed upon a hone 14 and pushed across it, the blade raised, the handle turned between the thumb and finger, the other side of the blade presented to the hone, and the operation 50 repeated until a desired edge has been secured. After this the blade is presented to a strop 15 which may be secured to the opposite side of the hone, as in Figure 4, and the blade drawn across the strop first on 55 one side, then on the other in a well-known manner. The construction of the device assures that the blade is held at the proper angle with respect to the hone or strop at all times when a lateral guide extension 6 or 7 and the edge of the blade 13 are in contact simultaneously with the hone or strop.

60 What I claim is:

65 1. A safety razor and blade holder, comprising, in combination, a handle having a threaded aperture therein, a pair of oppo-

sitely disposed bowed arms of semi-circular cross section integral with a threaded member to engage the threaded aperture in the handle, a ferrule surrounding the arms adjacent the handle, adjustable guide means 70 integral with the ferrule, parallel plates connected to the arms to grip a blade, guide means integral with each bowed arm to engage a sharpening means to position the blade gripped by the plates at a predetermined angle with respect to the sharpening means, and a safety blade holding device having a flat portion integral therewith with a pivot pin thereon, to be angularly adjustably connected to the blade holding 75 plates.

2. In a combined safety razor and blade holder, a handle, diverging arms removably secured thereto, a ferrule adjacent the handle and surrounding the diverging arms, convergent portions of said arms having parallel gripping members connected thereto, guide means integral with the diverging arms to maintain the gripping means at a predetermined angle with respect to a planiform surface in contact with the guide means and blade, and means to pivotally support a shaving device between the gripping members to shave with a stroke of a 90 determinable angle.

3. In a combined safety razor and blade holder, a handle, a ferrule adjacent thereto, lateral guide extensions integral with the ferrule, diverging arms of a predetermined curvature operatively associated with the 100 handle and the ferrule, converging extensions of said arms, gripping means carried by said extensions, a shaving device adjustably gripped by the gripping means, and means to grip a blade between the gripping means to position it at a predetermined angle to a planiform surface in contact with the edge and a predetermined portion of either of the diverging arms.

4. In a combined safety razor and blade 110 holder, a handle, diverging arms of a predetermined curvature having threaded engagement therewith, a converging arm integral with each diverging arm, gripping means carried by said converging arms, 115 means to relatively move the diverging arms to actuate said gripping means, adjustable lateral guide means to determine by touch the plane of the gripping means, means to grip a pivoted shaving device by 120 the gripping means at a determinable angle with respect to the handle, and means to grip a blade by said gripping means and guide it at a predetermined angle across a 125 planiform surface in contact with the edge of the blade and predetermined portion of either of the diverging arms.

5. In a combined safety razor and blade holder, a handle, a ferrule adjustably positioned adjacent thereto, lateral extensions 130

integral with the ferrule, diverging arms operatively associated with the handle and the ferrule, a converging portion of each of said arms, parallel gripping means supported by said converging arms, a shaving device adjustably gripped by the gripping means, a guide member associated with each

diverging arm, and means to position a blade between the gripping means at a predetermined angle to a planiform surface in contact with the edge of the blade and either of said guide members.

In testimony whereof I affix my signature.

CHARLES W. JONES.
